PRINTING LAMP OR THE LIKE

Earl C. Cunningham, Jr., Philadelphia, Pa., assignor to Macbeth Arc Lamp Company, Philadelphia, Pa., a corporation of Pennsylvania

Filed May 5, 1960, Ser. No. 60,463

Term of patent 14 years

(Cl. D48—20)

FIG.5.

FIG.6.

FIG.1.

FIG. 4.

FIG. 2.

FIG. 3.

Fig. 1 is a perspective view of the printing lamp, showing my new design;

Fig. 2 is a side elevational view thereof;

Fig. 3 is a front elevational view thereof;

Fig. 4 is a rear elevational view thereof;

Fig. 5 is a plan view from above thereof;

Fig. 6 is a sectional view taken along line 6—6 of Fig. 3; and

Fig. 7 is a fragmentary rear perspective view thereof.

I claim:

The ornamental design for a printing lamp or the like, as shown.
